CLAIM

The ornamental design for a surface configuration of a gearshift knob for a vehicle, as shown and described.

DESCRIPTION

This application is related to the following co-pending applications, of the inventors, filed on even date herewith and entitled "Surface Configuration of a Gearshift Knob for a Vehicle": U.S. patent application Ser. No. 29/166,311; U.S. patent application Ser. No. 29/164,866; and U.S. patent application Ser. No. 29/164,867.

FIG. 1 is a front, left perspective view of a surface configuration of a gearshift knob for a vehicle according to our novel design, the right, front perspective view being mirror symmetrical;

FIG. 2 is a left side view of the surface configuration of a gearshift knob for a vehicle according to our novel design, the right side view being mirror symmetrical;

FIG. 3 is a rear view of the surface configuration of a gearshift knob for a vehicle according to our novel design; and,

FIG. 4 is a top view of the surface configuration of a gearshift knob for a vehicle according to our novel design.
